US00D649400S

(12) **United States Design Patent**
Sands

(10) **Patent No.:** **US D649,400 S**
(45) **Date of Patent:** **** Nov. 29, 2011**

(54) **KITCHEN FOOD PROCESSOR CONTAINER**

(75) Inventor: **Lenny Sands**, Los Angeles, CA (US)

(73) Assignee: **Baby Bullet, LLC**, Los Angeles, CA (US)

(**) Term: **14 Years**

(21) Appl. No.: **29/394,457**

(22) Filed: **Jun. 16, 2011**

Related U.S. Application Data

(63) Continuation of application No. 29/381,541, filed on Dec. 20, 2010, now abandoned.

(51) **LOC (9) Cl.** **07-02**

(52) **U.S. Cl.** **D7/413; D7/376; D7/378; D7/384; D7/412**

(58) **Field of Classification Search** ..... **D7/305-313, D7/317-318, 368, 372, 376-386, 412-415, D7/665; D14/403; D19/73; D22/122; D27/106; 99/326, 348, 508-511; 241/30-37.5, 101.01-101.2, 241/166-169.1, 282.2, 285.1-285.3, 291, 241/292.1; 366/64-67, 98, 142, 197-211, 366/241-254, 279-292, 341-347; 416/75-76, 416/70 R, 163**

See application file for complete search history.

(57) **CLAIM**

The ornamental design for a kitchen food processor container, as shown and described.

DESCRIPTION

FIG. 1 is a front view of the kitchen food processor container; FIG. 2 is a right side view of the kitchen food processor container shown in FIG. 1;

FIG. 3 is a left side view of the kitchen food processor container shown in FIG. 1;

FIG. 4 is a rear view of the kitchen food processor container shown in FIG. 1, wherein the smiley face located on the front is seen through a transparent material structure in the rear view;

FIG. 5 is a top view of the kitchen food processor container shown in FIG. 1;

FIG. 6 is a front view of the kitchen food processor container with the blender cup shown in isolation;

FIG. 7 is a right side view of the kitchen food processor container shown in FIG. 6;

FIG. 8 is a left side view of the kitchen food processor container shown in FIG. 6;

FIG. 9 is a rear view of the kitchen food processor container shown in FIG. 6, wherein the smiley face located on the front is seen through a transparent material structure in the rear view; and,

FIG. 10 is a top view of the kitchen food processor container shown in FIG. 6.

The broken line portions of the disclosure are to illustrate environmental structure and form no part of the claimed design.

1 Claim, 10 Drawing Sheets
